SECTIONAL SPRING MATTRESS

Jennie Eichthaler, Broadwater, Nebr.

Application December 20, 1938, Serial No. 246,817

2 Claims. (Cl. 5—302)

This invention relates to that class of furnishings incorporated in beds, couches, seats and the like, by which comfort and ease to their users is attained.

- 5 An object of the invention is to provide a novel type of spring support structure so arranged in sections as to permit dismemberment and compact folding into small compass for storage, cleaning, transportation, and like purposes.
- 10 A further feature is in the provision of a sectional spring mattress unlimited in length and separable at will by mere manual operations, no tools or appliances being required.

Another purpose is to produce a spring mattress that may be reversed in position, shortened or lengthened by removal or addition of its sections, and which is yielding and comfortable in use.

These meritorious objects are accomplished by the novel and practical construction and arrangement of parts hereinafter described and illustrated in the accompanying drawing, constituting an essential component of this disclosure and in which:

25 Figure 1 is a perspective view of an embodiment of the invention.

Figure 2 is a fragmentary view in perspective indicating the detachable section engaging means.

30 Figure 3 is a similar view of the frame and clamping device.

Figure 4 is a sectional view taken on line 4—4 of Figure 3.

In ordinary domestic establishments, hotels, and rooming houses, it is frequently necessary to move a bed from one room to another, and as it is not usually possible to pass a complete bed through an ordinary door, recourse must be had to taking the bed apart, carrying the head and foot elements individually, and the common springs, including its rigid, full length frame, by two or more persons as best they can.

The prime object therefore of the present invention is to provide a sectional spring mattress 45 easily moved by one person by separation of its several sections.

In the annexed drawing the mattress is shown as consisting of three sections A—B—C, although obviously a greater or lesser number 50 may be used.

The end sections A and C are alike, each having spaced end bars 15—16, transverse to the structure as an entity, these bars connected by upright spacers 17.

55 Extending from the intersections of the bars

and spacers are horizontal bars 18—19, disposed longitudinally of the mattress, and connected at their ends by spacers 20 similar to the spacers 17.

The length of the bars 18—19 determines the 5 length of the sections, as will be apparent, and these bars may be further reenforced by other spacers 21 intermediate their lengths.

The intermediate section B consists of rectangular end frames composed of horizontal bars 10 22 connected at their ends by vertical spacers 23 and intermediate spacers 24, the latter having cross connecting rods 21' midway their height.

The spacers 20 and 23 are held in assembled 15 relation by clamps disposed midway their height, each clamp consisting of a sleeve 25 surrounding either of the spacers and carrying an eccentrically mounted pivot pin 26.

Journaled on the extending ends of the pin 20 is the inreaching hub portions 27 of a ink 28 20 terminating in a hook 29 adapted to engage partially around the adjacent spacer in such manner that when the sleeve 25 is partially rotated, by its handle, 30, the spacers are drawn towards one another and rigidly held by the clamp. 25

A plurality of slats 35 extend cross-wise the mattress, each slat having a series of holes 36 to receive the ends of helically wound tension springs 37, the opposite ends of spring engaging similar openings in the adjacent slats, except those at the ends which are secured to the end or side bars 15—16—18—19 in an appropriate manner as illustrated.

However, one of the slats at adjacent sections 35 has openings 38 accessible for the hooked ends 39 of the adjacent springs 37 by reason of recesses 40, thus providing means for the connection or disassociation of adjacent sections, as best seen in Figure 2.

Although the foregoing is generally descriptive 40 of the best known embodiment of the invention, minor changes are permissible within the scope of the appended claims.

Having thus described the invention and set forth the manner of its construction and use, 45 what is claimed as new and sought to secure by Letters Patent is:

1. A spring mattress comprising a plurality of narrow transverse sections each section having a rectangular frame including upright corner 50 members, a series of cross slats in each section, coiled tension springs interconnected between said slats and frame, and clamps having hooks for clamping the upright members of adjacent sections to constitute an entity. 55

2. A reversible spring mattress comprising pairs of end frames, an intermediate frame, all of said frames elongated rectangles disposed transversely of the mattress, and having spacers between their upper and lower members, said end frames having connecting bars at their outer extremities, a plurality of slats extending transversely the mattress between said frames at both sides thereof, coiled tension springs supporting-

ly connecting said slats and frames, other springs connecting adjacent slats, means carried by the adjacent corner spacers of said end frames to clamp the corresponding spacers of the intermediate frame, and springs on the innermost slats of said end frames to removably engage the adjacent slats of said intermediate frame. 5
